UNITED STATES PATENT OFFICE.

JOHANNES TH. PEDERSÉN, OF WOODSIDE, NEW YORK, ASSIGNOR TO PEDERSEN MANUFACTURING COMPANY, OF NEW YORK, N. Y., A CORPORATION OF NEW YORK.

LUBRICATOR.

No. 874,114.

Specification of Letters Patent.

Patented Dec. 17, 1907.

Application filed February 21, 1907. Serial No. 358,545.

To all whom it may concern:

Be it known that I, JOHANNES THEODORE PEDERSÉN, a citizen of the United States, residing at Woodside, in the county of Queens, 5 city and State of New York, have invented an Improvement in Lubricators, of which the following is a specification.

My invention relates to force feed or power actuated oil feeding devices or lubricators 10 adapted for supplying lubricating oil in regulatable quantities to various kinds of machines, especially motor vehicles, motor boats, etc., where high speed demands constant lubrication visually assured and apparent, and the same is an improvement upon the devices described and shown in Letters 15 Patent granted to me May 15, 1906, No. 820,821, with the object of simplifying, compacting and increasing the efficiency of the 20 devices of said patent.

The lubricating device of my present invention comprises essentially a series of oscillating cylinders in a suitable body-frame or support, a series of longitudinally movable 25 pistons or plungers in said cylinders, means for imparting movement to said pistons and cylinders, a receptacle for oil within which said parts are placed and supported, means at one end of said cylinder and pistons for 30 drawing in the oil from the receptacle and forcing it to and through suitable sight feed devices, and means at the other ends of said cylinders or pistons for receiving the oil from the sight feed devices and forcing it to the 35 desired parts of the machinery to be lubricated.

The parts to which power and rotation are communicated from the machinery are similar to similarly acting parts shown and described in my aforesaid patent.

In the drawing, Figure 1 is a vertical cross section and partial elevation and Fig. 2 a vertical longitudinal cross section and partial elevation showing the devices of my improvement; the section Fig. 1 being longitudinally of the oil receptacle and Fig. 2 being transversely of the oil receptacle. Fig. 3 is a sectional plan on the dotted line x, x , of Fig. 2. Fig. 4 is a vertical cross section at 45 the dotted line y, y , of Fig. 2. Fig. 5 is a vertical cross section on the dotted line z, z , of Fig. 2. Fig. 6 is a sectional plan and Fig. 50 A shaft f passes through a bearing f^1 in the back a^1 of the reservoir and on the forward end of this shaft is a worm g ; the said shaft f

7: an end elevation of a modified form of my invention.

The receptacle or reservoir for holding the 55 oil and for inclosing the devices hereinafter described is preferably composed of a front a , back a^1 , ends a^2 and a bottom portion a^3 . This reservoir is broken off so that the top is not shown. This top or upper end may be 60 of any desired form and will advantageously support the sight feed devices as shown in my aforesaid patent, and through which sight feed devices the oil passes where its progress can be visually noted and the fact that lubricating oil is flowing to the parts to be lubricated will be apparent and visually assured.

b represents a body frame of metal and b^1 auxiliary frames each including a stem 2, a nut 3, the stem entering a slot 4 of the body 70 frame b and the auxiliary frame by means of the clamping nut 3 being securely held to the body frame, said auxiliary frame having a flat under surface resting upon the flat surface of the body frame and the said body 75 frame is made with end frames b^2 .

c represents a bracket having a base adapted to be secured to the upper surface of the body frame b and c^1 c^2 are bearing sleeves formed therewith and at right angles to and 80 slightly off-set from one another.

d are a series of pipes entering the oil reservoirs through the bottom, secured thereto by clamping nuts. The upper ends of these pipes d are threaded and they enter alined 85 apertures in the body portion. e represents other series of pipes threaded at their lower ends and entering apertures in the body frame in line with the corresponding pipes d . These pipes e pass up and are intended to 90 pass through the cover from the receptacle into the sight feed devices that may be employed in connection with the devices of my present improvement and such as are shown and described in my aforesaid patent. 95 These series of pipes d e serve as supports for the body frame b and auxiliary frames b^1 and the end frames b^2 in the receptacle,—maintaining the same rigidly in the desired position and at a predetermined height from the 100 bottom of the oil reservoir.

A shaft f passes through a bearing f^1 in the back a^1 of the reservoir and on the forward end of this shaft is a worm g ; the said shaft f

passing through the bearing sleeve c^1 of the bracket c for support and guidance.

A worm-wheel h meshes with the worm g of the shaft f and the said worm-wheel is 5 upon the shaft h^1 placed vertically and passing through the bearing sleeve c^2 for support and guidance and at its upper end rising and being advantageously constructed as shown in my aforesaid patent, in which the duplicate 10 of this shaft passes through the cover and is shown as adapted to be provided with a manually actuated crank whereby the said shaft may be rotated by hand. In fact in Fig. 1 the upper end of this shaft is shown as 15 solid and adapted for connection with the crank. I employ a crank arm i secured on the lower end of the upright shaft h^1 below the bearing sleeve c^2 . This crank arm is slotted as shown in Figs. 1 and 2, and as will 20 also appear by reference to the aforesaid patent.

A rock-shaft k is provided with a pin k^1 entering and passing through the slot of the crank arm i . This rock-shaft is longitudinally 25 movable in the end frames b^2 and it is given a turning or oscillating movement as well as a longitudinal movement by the rotation of the crank arm i and a movement imparted thereby to the pin k^1 , said pin being 30 immovably fixed in the rock-shaft k . In the under surface of this rock-shaft I provide a series of apertures 5 and in opposite faces of the body frame b and auxiliary frames b^1 and in line with one another I provide a series of 35 tapering recesses which receive the tapering ends of the cylinders m , and in the device of my improvement I may employ any number of cylinders forming a series, and one of the objects of making the auxiliary frames separate 40 from the body frame and adjustable is to cause a close fitting taper bearing between the respective ends of the series of cylinders m and the tapering recesses in said parts receiving the same. These cylinders are longitudinally 45 slotted each to receive a pin 6 and a piston l fits each cylinder; the pin being fast in the piston and projecting beyond the cylinder into an aperture 5 of the rock-shaft k . These pistons are longitudinally movable 50 or reciprocating and they oscillate with the oscillation of the cylinders; said movements being caused by the oscillation of the rock-shaft k and its longitudinal movement. These cylinders and pistons form pump devices 55 for drawing the oil from the reservoirs and forcing it through the sight feed devices and also for receiving the oil from the sight feed devices and forcing it to parts of the machinery to be lubricated.

60 Referring particularly to Figs. 2, 4 and 5, I provide a port 7 in one end of each cylinder with an adjacent opening and a second similar opening through a foot portion of the auxiliary frame b^1 and an intake pipe o passing through the body frame b in line with the

first aforesaid port 7, and through the body frame I provide conduits 10 having portions at right angles to one another and discharge pipes c^1 which enter the upper portion of the body frame and rise to pass through the 70 cover and connect with sight feed devices such as I have shown and described in my aforesaid Letters Patent. At the other or left hand end of the cylinders m and with special reference to Fig. 5, I provide the 75 ports 8 9. Fig. 5 shows the port 8 as alining with the port from the pipe d , and the port 9 as closed off from alinement with the pipe e . This represents one position of the oscillating cylinder and in its other position the 80 port 9 alines with the pipe e and the port 8 is closed off from the pipe d . Likewise referring to Fig. 4, this shows the port 7 alining with the opening from the pipe o , and in its other position the port 7 will aline with the 85 opening from the conduits 10.

A modification of the form of my invention shown in Figs. 6 and 7, illustrates an end of a cylinder m^1 as closed by a perforated plug or disk m^2 ; this cylinder being preferably received in a recess of the body frame. The plug or disk m^2 is provided with two ports 11 and 12 and the body frame with ports 13 and 14 having portions at right angles to one another. Fig. 7 shows one position of the 90 oscillating cylinder in which the port 11 is concentric to the port 13 and the port 12 offset from the port 14. In the other position of this cylinder m^1 the port 12 will be concentric to the port 14 and the port 11 closed off 95 from the port 13.

I have hereinbefore generally described the operation of the device of my present invention with reference to the parts thereof, that is to say, the rotation of the shaft f and the worm g turns the worm-wheel h and the shaft in the slotted crank arm i , the pin k^1 on the rock-shaft acting by the rotation of the crank arm i and these parts acting upon the pin 6 in the apertures 5 of the rock-shaft 100 impart a reciprocating movement to the series of pistons l and oscillating movements to both the series of pistons and the series of cylinders so that in the position shown in Fig. 2 the oil from the receptacle is drawn by 105 the pipe o through the port 7 into the right hand ends of the cylinders m and at the other end of said cylinders the oil is forced through the port 8 and by the pipes d to the machinery to be lubricated. With the 110 movement of the pistons l in the opposite directions and the turning movement of the cylinders the ports 7 aline with the openings to the conduits 10 and the ports 9 aline with the openings to the pipes e and the oil in the 115 right hand end of the cylinders, Fig. 2, is forced by the conduits 10 into the sight feed devices, returning by the pipes e , through the ports 9 into the chambers in the opposite ends of the cylinders m , so that when the 120

130

5 pistons move again in the opposite direction and the cylinders oscillate the ports are brought again into the position shown in Figs. 4 and 5, in which oil is drawn in from the receptacle and forced by the pipes *d* to the machinery to be lubricated.

It is sometimes necessary to construct a lubricating device adapted to force a large number of streams of oil to many distant 10 places for lubricating parts of machinery and it is necessary to put this lubricating device into as small a compass as possible, and the device of my present invention is adapted to be put into a very much smaller compass 15 than the devices of my hereinbefore named patent and this comes about in a large measure because there is no reciprocating frame support with which the series of cylinders and pistons move, for from the foregoing 20 it will be apparent that the only movable part in the present case is the rock-shaft *k*, consequently the series of cylinders and their pistons in the stationary body frames can be placed as close together as is consistent 25 with the independent movement of each; Figs. 1 and 2 of the drawing illustrate that the series of pipes *e* and *o*¹ are in separate lines and staggered with reference to one another in order to be more compact.

30 I have herein shown and described a series of oscillating cylinders and a series of oscillating and reciprocating pistons within the cylinders and means for operating the same because such series will usually be employed 35 in devices of this character for the reason that it is advantageous to force lubricating oil from a source of supply to numerous adjacent or nearby places for the lubrication of machinery and to do the same automatically. These devices may be employed and this act performed regardless of whether 40 sight feed devices are employed for visually denoting the flow of the lubricating material or not. Furthermore, these devices are of 45 small size and the series can be put into a small compass. It is obvious however, that the structure of my invention is equally adapted for forcing liquid or fluid in regulatable quantities from the source of supply. 50 It is also obvious that the proportions of the parts are only questions of degree and that the same construction of greatly exaggerated size may be employed singly or in series actuated in the same or substantially 55 the same manner for the purpose of forcing liquid or fluid from a source of supply to a source of use or predetermined point, and from this it will be apparent that the features of my invention are broader than the 60 series of devices.

I claim as my invention:—

1. In a lubricating device and in combination, a series of oscillating cylinders, a series of reciprocating and oscillating pistons within 65 said cylinders, means for simultaneously

moving the said cylinders and pistons, a power device for actuating the same, a body frame serving as a support for the said cylinders and means for conveying the oil to and from the respective ends of the cylinders 70 and pistons with the movement of the pistons.

2. In a lubricating device and in combination, a series of oscillating cylinders, a series of reciprocating and oscillating pistons within 75 said cylinders, means for simultaneously moving the said cylinders and pistons, a power device for actuating the same, a body frame serving as a support for the said cylinders, a pipe for the inlet of oil to one end of 80 the said cylinders, a channel through the body portion from the same end of the cylinders and a pipe leading therefrom, a pipe leading into and a pipe leading out from the other end of said cylinder. 85

3. In a lubricating device and in combination, a series of oscillating cylinders, a series of oscillating and reciprocating pistons within 90 said cylinders, means for simultaneously moving the cylinders and pistons of said series, a body frame receiving the cylinders of the series at one end, auxiliary frames adapted to receive the opposite ends of said cylinders and means for connecting the same in an adjustable relation to the body frame 95 and means providing for the entrance of oil and its exit from the respective ends of the cylinders of said series with the movement of said pistons.

4. In a lubricating device and in combination, a series of oscillating cylinders, a series of oscillating and reciprocating pistons within 100 said cylinders, means for simultaneously moving the cylinders and pistons of said series, a body frame receiving the cylinders of the series at one end, auxiliary 105 frames adapted to receive the opposite ends of said cylinders and means for connecting the same in an adjustable relation to the body frame, a pipe for the inlet of oil to one end of the said cylinders, a channel through the body portion from the same end of the cylinders and a pipe leading therefrom, a pipe leading into and a pipe leading out from the other end of said cylinder. 110

5. In a lubricating device and in combination, a series of oscillating cylinders longitudinally and centrally apertured, a series of oscillating and reciprocating pistons within 115 said cylinders, pins connected to the pistons 120 and passing through slots of the cylinders, a reciprocating rock-shaft having a series of apertures in the under surface receiving the said pins, and power devices for rocking the said shaft and reciprocating the same for imparting an oscillatory movement to the cylinders and pistons and also a reciprocating movement to the pistons. 125

6. In a lubricating device and in combination, a series of oscillating cylinders longi- 130

tudinally and centrally apertured, a series of oscillating reciprocating pistons within said cylinders, pins connected to the pistons and passing through slots of the cylinders, a reciprocating rock-shaft having a series of apertures in the under surface receiving the said pins, a suitable support for the aforesaid parts, a pin projecting from the rock-shaft, a crank-arm, a shaft connected thereto, a shaft at right angles to the said shaft, a worm-wheel and worm connecting the said shafts and bearings for the shafts whereby with the rotation of the crank-arm the rock-shaft and the pin thereof in the slot of the crank-arm are operated.

7. In a lubricating device, the combination with a suitable receptacle for holding a supply of lubricating material, of a body frame within the same provided with a series of alined recesses and a series of conduits, a series of auxiliary frames having recesses and means for connecting the auxiliary frames to the body frame so that the recesses are alined, series of oscillating cylinders received in said recesses, a series of pistons in said cylinders, means for imparting an oscillatory movement to the cylinders and a reciprocating movement to the pistons, pipes entering the body frame at one end of the cylinders and communicating with the interior of the cylinders at their said ends and having apertures at the same ends communicating with the aforesaid conduits for drawing in the oil of the receptacle and forcing the same through the conduits, pipes entering the body frame in opposite directions at the opposite ends of the said cylinders, and the body portion having openings communicating with said pipes and the interior of the cylinders at said ends for receiving and discharging oil and which pipes act as supports for the body frame.

8. In a lubricating device, the combination with a suitable receptacle for holding a supply of lubricating material, of a body frame within the same provided with series of alined tapering recesses and a series of conduits, a series of auxiliary frames having tapering recesses and means for connecting the auxiliary frames to the body frame so that the recesses are alined, series of oscillating cylinders having tapering ends received in said recesses, a series of pistons in said cylinders, means for imparting an oscillatory movement to the cylinders and a reciprocating movement to the pistons, pipes entering the body frame at one end of the cylinders and communicating with the interior of the cylinders at their said ends and having apertures at the same ends communicating with the aforesaid conduits for drawing in the oil of the receptacle and forcing the same through the conduits, pipes entering the body frame in opposite directions at the opposite ends of the said cylinders, and the body frame having openings

communicating with said pipes and the interior of the cylinders at said ends for receiving and discharging oil and which pipes act as supports for the body frame.

9. In a lubricating device, the combination with a suitable receptacle for holding a supply of lubricating material, of a body frame within the same provided with a series of alined recesses and a series of transversely placed conduits, a series of auxiliary frames having recesses and means for connecting the auxiliary frames to the body frame so that the recesses are alined, series of oscillating cylinders received in said recesses, a series of pistons in said cylinders, means for imparting an oscillatory movement to the cylinders and a reciprocating movement to the pistons, pipes entering the body frame at one end of the cylinders and communicating with the interior of the cylinders at their said ends and having apertures at the same ends communicating with the aforesaid conduits for drawing in the oil of the receptacle and forcing the same through the conduits, pipes entering the body frame in opposite directions at the opposite ends of the said cylinders, and the body portion having openings communicating with said pipes and the interior of the cylinders at said ends for receiving and discharging oil and which pipes act as supports for the body frame, the latter pipes serving as supports for the body frame in and to the said oil receptacle.

10. In a lubricating device, the combination with a suitable receptacle for holding a supply of lubricating material, of a body frame within the same provided with a series of alined tapering recesses and a series of transversely placed conduits, a series of auxiliary frames having tapering recesses and means for connecting the auxiliary frames to the body frame so that the recesses are alined, series of oscillating cylinders having tapering ends received in said recesses, a series of pistons in said cylinders, means for imparting an oscillatory movement to the cylinders and a reciprocating movement to the pistons, pipes entering the body frame at one end of the cylinders and communicating with the interior of the cylinders at their said ends and having apertures at the same ends communicating with the aforesaid conduits for drawing in the oil of the receptacle and forcing the same through the conduits, pipes entering the body frame in opposite directions at the opposite ends of the said cylinders, and the body portion having openings communicating with said pipes and the interior of the cylinders at said ends for receiving and discharging oil and which pipes act as supports for the body frame.

11. A device for forcing fluid or liquid from a receptacle therefor to a place separated therefrom, the same comprising an oscillating cylinder, a support therefor having

bearings for the ends of the cylinder, a reciprocating piston within the said cylinder and a unitary means directly connected to one of said parts for simultaneously oscillating the cylinder and reciprocating the piston.

12. A device for forcing fluid or liquid from a receptacle therefor to a place separated therefrom, the same comprising an oscillating cylinder, a support therefor having 10 bearings for the ends of the cylinder, a reciprocating piston within the said cylinder, a unitary means for simultaneously oscillating the cylinder and reciprocating piston and suitable ports connected with the support for 15 the cylinder at the respective ends thereof for drawing into the cylinder the fluid or liquid and by which the same is forced therefrom.

13. A device for forcing fluid or liquid 20 from a receptacle therefor to a place separated therefrom, the same comprising an oscillating hollow cylinder, a support for said cylinder recessed to receive the respective ends thereof and in which bearings are 25 formed, a reciprocating piston in said cylinder, a pin in the said piston passing through a longitudinal slot in the said cylinder, a unitary device engaging said pin for reciprocating the piston and simultaneously oscillating 30 the cylinder, and suitable ports in the said support communicating with the interior of the cylinder at its ends whereby the liquid or fluid may be drawn in and forced out by the action of the piston.

35 14. A device for forcing fluid or liquid from a receptacle therefor to a place separated therefrom, the same comprising an oscillating hollow cylinder, a body frame recessed to receive one end of the cylinder and

forming a bearing therefor, an auxiliary frame recessed to receive the other end of said cylinder and forming a bearing therefor, means for connecting the body frame and auxiliary frame, a reciprocating piston in said hollow cylinder, a unitary device for 40 simultaneously oscillating the said cylinder and reciprocating the said piston, ports passing through the body frame and auxiliary frame and communicating into the respective ends of the hollow cylinder whereby with the 45 movement of the piston the fluid or liquid is drawn in and forced out.

15. A device for forcing fluid or liquid from a receptacle therefor to a place separated therefrom, the same comprising an oscillating hollow cylinder, a body frame recessed to receive one end of the cylinder and forming a bearing therefor, an auxiliary frame recessed to receive the other end of said cylinder and forming a bearing therefor, means for connecting the body frame and auxiliary frame, a reciprocating piston in said hollow cylinder, a pin projecting from the piston through a slot placed longitudinally in the hollow center, a unitary device 60 engaging said pin for simultaneously reciprocating the piston and oscillating the cylinder, ports passing through the body frame and auxiliary frame and communicating with the respective ends of the hollow cylinder whereby with the movement of the piston the fluid or liquid is drawn in and forced out.

Signed by me this 11th day of February 1907.
